UNITED STATES PATENT OFFICE.

LOUIE T. LA PAUGH, OF UTICA, NEW YORK.

OUTLET-BOX.

No. 854,046.

Specification of Letters Patent.

Patented May 21, 1907.

Application filed February 7, 1906. Serial No. 299,955.

To all whom it may concern:

Be it known that I, LOUIE T. LA PAUGH, a citizen of the United States, residing at Utica, in the county of Oneida and State of New York, have invented certain new and useful Improvements in Outlet-Boxes; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in outlet boxes for electric conduits, and consists in the provision of a novel manner of fastening the cover to the box, involving a saving of labor and material and providing a secure and inexpensive fastening means, doing away with inwardly or outwardly bent ears which are commonly formed upon junction boxes and which are frequently liable to break off.

In order to make steel drawn boxes with ears bent at right angles to the wall of the box, a very ductile and high grade steel must be used, and in so doing, the operation of blanking and drawing a box without heating or reheating, hardens the steel to such a degree that it is very difficult to bend the parts of the box at right angles to the sides without breakage, for the reason that the operation of drawing a box out of one piece of steel will necessarily destroy or weaken the fiber of the metal, thereby weakening the ears at the point of bending, and it is the aim of the present invention to produce a box without any inwardly or outwardly extending lugs, to obviate these objections.

More specifically, the present invention contemplates the provision of a fastening means for covers consisting of screw-eyes which have threaded connection with apertures in the bottom of the box, while the shank portion of the screw extends through an aperture or slot in the cover, while the eye of the screw projecting beyond the cover, forms means whereby the same may be securely anchored to the plastering of a wall.

The invention consists further in other details of construction which will be hereinafter fully described and then specifically defined in the appended claims.

I illustrate my invention in the accompanying drawings, in which:

Figure 1 is a perspective view of an outlet box made in accordance with my invention. Fig. 2 is a perspective view showing the cover and the box disassembled. Fig. 3 is a perspective view showing the invention as applied to a square box, the parts being disassembled. Fig. 4 is a perspective view of a detail, showing a lug upon the cover to prevent lateral movement of the latter. Fig. 5 is a sectional view through a box and cover and illustrating a slightly modified form of means for holding the cover to the box, and Fig. 6 is a perspective view of the form of cover and box illustrated in Fig. 5, with the parts disassembled.

Reference now being had to the details of the drawings by letter, A designates a circular-outlined outlet box having the usual openings B' therein which contain plugs adapted to be removed for the reception of conduit wires, and C designates the cover of the box which has the angled lugs D turned in from the marginal edge thereof and adapted to bear against the inner surface of the outlet box to hold the same from lateral movement. Said cover is provided with one or more slots F cut in from the edges thereof preferably at locations diametrically opposite, and threaded apertures G are formed in the bottom of the box and adapted to receive the screw-eyes H.

Referring to Fig. 3 of the drawings, will be seen a square-outlined outlet box having a plurality of angled lugs D formed about the edge thereof and designed to engage the inner surface of the side wall of the box to prevent lateral play of the cover, and said cover is provided with slots F, as before described, and the bottom of the box is provided with threaded apertures G to receive the screws H.

In Fig. 4 of the drawings is illustrated a detail showing an angled lug D about the circumference of the cover as engaging the outer surface of the box instead of the inner, and in Figs. 5 and 6, I have shown an angled lug K formed about the marginal edge of the cover and engaging a slot N formed in the wall of the box while a portion of the box cover opposite is provided with the slot F to receive the shank portion of the screw H.

In adjusting the cover to the box, the lugs D upon one edge of the cover are inserted in the box and made to bear against the inner surface of the surrounding wall, the eyes of the screw being first turned so that they will pass

through the slots formed at locations diametrically opposite in the cover. The cover thus resting upon the box with the heads of the screws passing through said slots, the cover may then be securely held by turning the screws so that the eyes will be crosswise of the slots and bearing against the opposite walls thereof. The lugs E upon the circumference of the cover bearing against the wall of the box will serve to hold the same from lateral movement, while the screws holding the cover securely to the box with the eyes projecting beyond the cover, form means for anchorage in the plastering of a wall.

15 What I claim is:—

1. An outlet box having threaded apertures in the bottom thereof, fastening means extending through said apertures, and held by the threads of the latter and a cover having slots through which said fastening means pass, as set forth.

2. An outlet box having threaded apertures in the bottom thereof, screw-eyes, threaded portions of which are fitted in said

threaded apertures, and a cover having slots 25 therein adapted to receive said screws, the eyes at the ends of said screws adapted to be turned transversely across said slots to hold the cover upon the box, as set forth.

3. An outlet box having threaded apertures in the bottom thereof, screw-eyes fitted in said apertures, a cover having slots formed in the edge thereof adapted to receive said screws, and lugs formed about the circumference of the cover and adapted to 35 engage the wall of the box, the eyes of said screws designed to be turned crosswise of said slots to engage and hold the cover in place and serving as an anchorage means to hold the box in the plastering of a wall, as 40 set forth.

In testimony whereof I hereunto affix my signature in the presence of two witnesses.

LOUIE T. LA PAUGH.
